DECANTER

Robert E. Hennessy, Summit, N. J., assignor to National Distillers Products Corporation, New York, N. Y.

Application December 20, 1954, Serial No. 33,607

Term of patent 3½ years

(Cl. D58—6)

FIG. 3.

FIG. 1.

FIG. 2.

FIG. 4.

Fig. 1 is a front elevational view of a decanter, showing my new design;

Fig. 2 is a side elevational view;

Fig. 3 is a top plan view; and

Fig. 4 is a bottom plan view.

The rear and side views not shown are the same as those shown.

I claim:

The ornamental design for a decanter, as shown and described.
